UNITED STATES PATENT OFFICE.

LORA E. POOLE, OF ANDERSON, INDIANA, ASSIGNOR, BY MESNE ASSIGNMENTS, TO DELCO-REMY CORPORATION, OF DAYTON, OHIO, A CORPORATION OF DELAWARE.

ARMATURE-CORE-INSULATING MACHINE.

Application filed April 24, 1926. Serial No. 104,404.

This invention relates to the manufacture of armatures for dynamo electric machines, and particularly to the insulation of the armature core slots and of the conductors located within these slots.

The present invention is embodied in a novel process of making strips of armature core slot insulation from a flat strip of insulating material, and in apparatus for carrying out this process and for automatically inserting insulating strips within the slots of an armature. By the novel process and apparatus to be described, the chief objects of the present invention are accomplished, namely, to improve the product and reduce the cost of manufacture. The process and apparatus for making the core slot insulating members are described and claimed in divisional case No. 250,283, filed January 28, 1928.

Further objects and advantages of the present invention will be apparent from the following description, reference being had to the accompanying drawings, wherein a preferred form of embodiment of the present invention is clearly shown.

In the drawings:

Fig. 1 is a plan view of a machine embodying the present invention.

Fig. 2 is a side elevation looking in the direction of the arrow 2 of Fig. 1.

Figs. 3 to 10 inclusive are sectional views taken respectively on similarly marked section planes in Fig. 2.

Fig. 11 is an end elevation of the machine looking in the direction of arrow 11 of Fig. 1.

Fig. 12 is a sectional view on the line 12-12 of Fig. 11.

Fig. 13 is a sectional view on the line 13-13 of Fig. 12.

Fig. 14 is a sectional view on the line 14-14 of Fig. 13, this view being developed into a single plane instead of two planes as indicated in Fig. 13. Fig. 14 also shows a developed sectional view of an armature core and its rotatable support.

Fig. 14^a is a fragmentary end view of the armature as seen in the direction of the arrow 14^a in Fig. 14.

Fig. 15 is a side elevation, partly in section, of a feed roll operating mechanism, this view being taken on the line 15-15 of Fig. 1.

Fig. 16 is a sectional view on the line 16-16 of Fig. 15.

Figs. 17 and 18 are fragmentary sectional

views on the lines 17-17 and 18-18, respectively, of Fig. 16.

Referring to Figs. 3 to 10 inclusive the method of folding the paper to form slot insulation pieces will first be described. The flat strip of paper designated by numeral 20 in Fig. 3 is unwound from a supply roll, not shown, and is passed over a trough 21 which pivotally supports a weight member 22 tending to maintain the paper 20 flat within the trough. The paper is drawn from left to right as viewed in Fig. 2, and when it arrives approximately at the plane 4-4 of Fig. 2 it is passed between members 23, 24, 25 and 26 where its cross sectional shape 20^a becomes one which is similar to a slanting N. When the paper arrives at the section plane 5-5 of Fig. 2 it will pass between members 23, 27, 28 and 29 which causes the paper to be folded so that its cross sectional shape 20^b resembles that of a slanting N having less inclination to the vertical than in Fig. 4. It will be noted that the part 23 in Fig. 5 is the same member as part 23 in Fig. 4 but its cross sectional contour gradually changes from that shown in Fig. 4 to that shown in Fig. 5 in order that the paper will be given a different shape as it progresses from the left toward the right.

When the paper strip arrives at the plane 6-6 in Fig. 2 it passes between forming and feeding rolls 30 and 31 which give it the cross-sectional shape 20^c which might be characterized by likening it to an inverted U joined to an upright U or to a recumbent S. After the paper leaves the rolls 30 and 31 it passes into a flaring mouth 32 of a tunnel 33 which is oblong in cross-sectional shape with rounded ends as shown in Fig. 7. This tunnel 33 is provided by grooving two blocks

34 and 35 and placing them together as shown. The movement of the strip through the tunnel causes its shape to change from its cross-sectional shape 20^c to the cross-sectional shape 20^d, the latter shape resembling a relatively narrow upright S or a reversed S according to the direction in which the view is taken. After leaving the tunnel 33 the strip passes through a guide passage 36 provided in a rotatable work holder 40 which receives and supports an armature core 37 carried by a shaft 38 and provided with a plurality of slots 39. As the strips 20 are inserted into the slots 39, they are maintained in contact with the bottoms of slots, for a purpose to be

described later, by band 37^a which is placed temporarily around the armature core 37. The band 37^a is provided on its interior with longitudinally extending ribs 37^b which are spaced so that each will be received by a core slot 39.

Referring to Fig. 12, the work holder 40 is a cup-shaped member having a horizontally disposed shank 41 rotatably supported 10 by a bearing 42 attached to a bracket 43 which is mounted upon the base plate 44 of the machine. Endwise movement of the shank 41 is prevented by the engagement with the bearing 42 of a shoulder 45 provided by the 15 shank 41 and by a nut 46 engaging the threaded end 47 of the shank. The shank 41 is tubular and receives a rod 48 having a central recess 49 for receiving the armature shaft 38. The recess 49 is surrounded by three 20 resilient spring arms 50 integral with the rod 48. These arms cooperate with an internal conical surface 51 provided by the shank 41. Thus the shank 41 and the resilient members 50 constitute a collet chuck for gripping the 25 shaft 38 when the rod 48 is pulled toward the left so that the ends of the chucking jaws 50 will be forced against the conical surface 51 and will grip the shaft 38. The rod 48 is threadedly connected with a flanged nut 52. 30 A spring 53 located between the nut 52 and the nut 46 urges the rod 48 toward the left so that the shaft 38 will be gripped by the members 50. In order to release the chuck 35 so that the core and shaft may be removed from the machine, the operator will press a pedal not shown but connected with a lever 54 causing it to move in a clockwise direction. Levers 54 and 56 are attached to a shaft 55 supported by the base 44. Lever 56 is provided with a hole 57 which receives a pin 58 connected with a plate 59 which is adapted to bear against the nut 52. Obviously, downward movement of the lever 54 will be transmitted through the shaft 55 and the lever 56 45 causing it to move toward the right in order to compress the spring 53 and relieve the chucking jaws 50 from wedging engagement with the shank 41. The interior of the cup 40 is provided with a rib 60 which will be received by one of the core slots in order to 50 locate the core properly relative to the work holder.

The trough 21 is supported by a bracket 65 which also supports the parts 23 to 29 inclusive shown in section in Figs. 4 and 5. The guides 34 and 35 are supported by a bracket 66 and the bracket 43.

The feeding and folding rolls 30 and 31 are drivingly connected with shafts 70 and 60 71 respectively and are maintained in driving engagement therewith by nuts 72 and 73 respectively engaging threaded ends of the shafts. The shaft 70 is journaled in bearing blocks 74 which are supported for vertical 65 sliding movement by a bracket 75 supported

by the base plate 44. Each bearing block 74 is yieldingly urged downwardly by spring 76 which bears at its upper end against a washer 77 bearing against a nut 78 threadedly connected with a rod 79 having its lower end 70 connected with a plate 80 which is attached by screws 81 to the bracket 75. The lower end of the spring 76 bears against a disc 82 having studs 83 connected therewith, each stud 83 passing through a hole 84 in the plate 75 80 and bears at its lower end against the block 74. The shaft 71 is supported by bearings 85 carried by the bracket 75 and is drivingly connected with the shaft 70 by gears 86 and 87 connected respectively with shafts 71 and 70. The shaft 71 is supported also by bracket 88 mounted on the base plate 44.

The mechanism for imparting intermittent rotary motion to the shaft 71 in a clockwise direction as viewed in Fig. 15, comprises a 85 ratchet 90 attached to the shaft 71 and engageable with a plurality of pawls 91 each mounted on a stud 92 supported by a disc 93 which is rotatably supported by the shaft 71 but is not drivingly connected therewith. 90 Each pawl is urged toward the ratchet by a leaf spring 94 fixed at 95 to the periphery of the disc. The disc 93 is oscillated by a link 96 connected at one end with the disc and at the other end with a lever 97 rotatably supported by a stub shaft 98 carried by bracket 99 which is supported by the base 44. The lever 97 carries a cam following roller which is received by a slot 101 of a drum cam 102 which is mounted on a shaft 100 103. Obviously, for each rotation of the shaft 103 there will be one complete oscillation of the lever 97 and link 96. This movement will produce rotation of the feed rollers 30 and 31 then a backing up of the pawls by movement 105 in a counterclockwise direction preparatory to the next feeding operation. The ratchet 90 is prevented from backing up by a friction device including a drum 104 attached to the shaft 71 and engaged by a split clamping band 105 which is prevented from turning by the engagement of one of its lugs 107 with a post 106 attached to the base 44. The band 105 is urged into frictional engagement with the drum 104 by a spring 108 bearing against a lug 109 of the clamp and the head of a screw 110 which passes through plain holes in the lugs 107 and 109 and threadedly engages the post 106. Turning the screw 110 will vary the friction pressure exerted by the clamp 110 120 125 130.

The shaft 103 is supported by the bracket 43, a bracket 114 and a bracket 115. The shaft 103 is connectible with a shaft 116 by a clutch member 117 which is drivingly connected with the shaft 103 and is endwise movable into engagement with a clutch member 118 fixed to the shaft 116. The shaft 116 is supported by brackets 119 and 120 and is attached to a gear 121 meshing with a gear 130

122 which is supported by a shaft 123 operated by an electric motor 124 carried by the base plate 44. The clutch members 117 and 118 are engaged by means including a lever 125 which is pivotally connected with a bracket 126 attached to the base plate 44. The lever is connected by a link 127 with a lever 128 carrying a roller or stud 129 which is received by a groove 130 provided by the clutch member 117. The lever 128 is pivoted upon a post 131 attached to the base 44. A spring 132 connecting the lever 28 with the base plate 44 tends to disengage the clutch member 117 from the clutch member 118. To cause rotation of the shaft 103, the operator, who stands facing the end of the machine shown in Fig. 11, and therefore facing in the direction of the arrow 11 of Fig. 1, will push the lever 125 away from him in order to cause the link 127 to move toward the right in Fig. 1 and the lever 128 to move counterclockwise to engage the clutch 117 with the clutch 118. The motor 124 will then operate the shaft 103. The operator will maintain the lever 128 in this position manually until a cam 135, which is rotatably supported by a stub shaft 136 and is driven by the shaft 103 through gearing 137 and 138, has been rotated sufficiently to cause a notched portion 139 to move away from a roller 140 attached to the lever 128. Then the operator may release the lever 125 so that the spring 132 will draw the roller 140 into engagement with the outer periphery 141 of the cam 135. The shaft 103 will continue to rotate until the cam 135 has made substantially a complete revolution to bring the notch 139 opposite the roller 140. Then the spring 132 will be released to move the lever 128 clockwise in order to disconnect the clutch member 117 from the member 118.

Due to the rotation of the rollers to feed the paper endwise as well as to perform one of the steps of forming it, a portion of the strip of paper is fed through one of the guide passages 36 in work holder 40 into an armature core slot 39 in alignment therewith; this portion is severed from the remainder of the strip by means including a shear block 150 which cooperates with a slidible knife 151 which is guided by a bracket 152 attached to the bracket 43. The knife 151 is provided with a slot 153 for receiving a stud 154 carried by lever 155 which is supported by a pivot stud 156 carried by the bracket 43. The lever 155 carries a roller 157 which is yieldingly urged by a spring 158 against a cam 159 which is attached to the shaft 103. Spring 158 is connected with a screw 160 attached at one end to the lever 155 and to the other end with a bracket 161 attached to the bracket 43. Soon after the end of the paper feeding operation, the knife 151 will shear the paper at the adjacent edge of the shear block 150.

After the shearing operation, the operation of rotating the work holder 40 in a counter-

clockwise direction, as viewed in Fig. 11, is performed in order to bring the next core slot 39 opposite the tunnel 33. It will be understood that the shear block 150 is provided with a groove forming an extension of the groove in the block 33 so that the blocks 34 and 150 may cooperate with the block 33 to provide a tunnel forming an extension of the tunnel provided by the blocks 33 and 34 as described with reference to Fig. 7. The mechanism for intermittently moving the work holder in the manner described, comprises a crank pin 170 attached to the shaft 103, and a link 171 connecting the pin 170 with a stud 172 attached to a lever 173 having a hub 174 which is rotatably supported by the shank 41 of the work holder 40. The lever 173 carries a screw 175 providing a pivot for a ratchet pawl 176 which cooperates with ratchet teeth 177 provided by the periphery 85 of the work holder 40. A leaf spring 178 attached to the lever 173 bears against the pawl 176 in order to yieldingly maintain engagement with the ratchet 177. The shaft 103 is rotated in a clockwise direction as viewed in 90 Fig. 11, so that, after the knife bar 151 has sheared the paper and begins movement toward the right in Fig. 11, the lever 173 will start substantially at the same time to move in a counterclockwise direction in order that 95 the work holder 40 will be rotated through an angular distance substantially equal to the spacing of the guide slots 36. After the indexing of the work holder has been performed the next feeding operation will take place 100 during which the ratchet lever 173 will be moved clockwise an angular distance slightly greater than the spacing of the ratchet teeth 177. Rotation of the ratchet in a clockwise direction is prevented by a band 179 which 105 frictionally engages a cylindrical surface 180 provided by the work holder 40. The band is in the form of a split ring and may be adjustably clamped about the the work holder 40 by turning a screw 181 which passes 110 through a plain hole in the band lug 182 and threadedly engages the band lug 183. The band lug 182 is apertured to receive a stud 184 attached to the bracket 43 and cooperat- 115 ing with a nut 185 to prevent endwise move- ment of the band 179.

It is therefore apparent that each cycle of operation of the machine includes feeding a folded strip of paper into an armature core slot, the severing of that portion of the paper 120 within the armature core from the remaining portion, and the turning of the armature core relative to the paper feeding means in order that the next core slot to be insulated will be brought into alignment with the pas- 125 sage 33 through which the insulation strip is guided into the armature core. During the feeding operation, a portion of the strip of paper is being folded preparatory to being fed into the armature core during a succeeding 130

feeding of the operation. The machine will operate continuously until all of the armature core slots have been provided with insulation pieces. Then the machine will stop automatically. This is accomplished through the clutch control device described. If, for example, the armature core has 23 slots, the speed ratio of the gearing 137 and 138 is as 23 to 1. That is, the shaft 103 will make 23 revolutions in order to rotate the cam 135 once so that its notch 139 will be brought again opposite to the roller 140, thus permitting the clutch member 117 to be disengaged from the clutch member 118 by the operation of the spring 132.

Referring to Figs. 13 and 14, it will be apparent that it is not practical to locate the cutting edge of the knife bar 151 in the same plane as the left hand end of the armature core 37. Therefore a portion of the strip 20 measured by the distance between planes $x-x$, $y-y$ in Fig. 14 will project beyond the left hand end of the core 37. It is desirable to shove substantially all of the insulation pieces 20 through the core slots in order that the ends of the strips may be received by closed slots 190 located in alignment with the slots 39 of the armature core and provided in a non-conducting disc 191 located adjacent that end of the armature core which is to be remote from the commutator. The function of the disc 191 is to assist in maintaining the armature conductors within the core slots. The insulating disc 191^a which is placed against the end of the core which is to be adjacent the commutator may have open slots, since the soldered connections between the armature conductors and commutator risers will suffice to retain the conductors at the commutator end of the core. After each insulating strip 20 has been pushed through the core so that its right hand end will be received by a closed slot 190 of the non-conducting disc 191 that end will be prevented from coming out of the armature core. It will now be apparent that the ring 37^a will facilitate movement of the insulation pieces through the closed slots of the end non-conducting disc 191, since the ribs 37^b provided by the ring 37^a maintain the strips 20 against the bottoms of the core slots 39. After the strips 20 have been moved past the shear block 150 they are shoved further toward the right in Fig. 14 by means including a bar 192 which is slidably supported by guide block 193 for endwise movement parallel to the direction of movement of the strip 20. Endwise movement of the bar 192 toward the strips 20 in order to push them further into the armature core as shown in Fig. 14 is produced by a plate cam 194 having a beveled surface 195 which cooperates with a beveled surface 196 which defines a notch 197 with which the bar 192 is provided for receiving the cam 194. The cam 194 is attached by screw 198 to the lever

173. Therefore during clockwise rotation of the lever 173 the slide 192 is moved toward the right in Fig. 14 in order to move a strip 20 further into the armature core 37. During counterclockwise movement of the lever 173 the slide 192 is moved toward the left by spring 199 bearing at one end against the guide block 193 and at the other end against a shoulder 200 provided by a rod 201 which is attached to the bar 192. The guide block 193 is attached by screws 202 to the bracket 43.

Obviously, it would be necessary where a 23 slot core is loaded to operate the machine 27 cycles before stopping in order that all of the strips 20 would have the same location 80 relative to the core 37 as the strips 20' in Fig. 14. This has not been found necessary as it is a relatively simple matter to push in the strips 20'' after the core 37 has been removed from the work holder 40. If the machine 85 were caused to operate 27 cycles for the purpose specified it would of course be necessary to discontinue the operation of the paper feeding mechanism after 23 cycles.

In order to facilitate threading the end of 90 the paper strip after it leaves the feeding and folding wheels 30 and 31 into the tunnel 33 between the blocks 33 and 34 as shown in Fig. 1, the guide block 33 is mounted to rotate about a vertical pivot stud 210 which is supported by the bracket 43. The guide block 33 is maintained in the position shown by a U-shaped clip 211 having its branches engaging its vertical outsides of the guide blocks 95 33 and 34.

While the form of embodiment of the present invention as herein disclosed, constitutes a preferred form, it is to be understood that other forms might be adopted, all coming 105 within the scope of the claims which follow.

What is claimed is as follows:

1. Armature core insulating apparatus comprising, in combination, means for supporting a slotted armature core, means for folding a flat strip of non-conducting material into the form required for slot insulation and for intermittently feeding the folded strip into a core slot, and mechanism for automatically producing intermittent movement of one means relative to the other 110 in order that the core slots will successively receive a folded strip.

2. Armature core insulating apparatus comprising, in combination, means for rotatably supporting a slotted armature core, 120 means for folding a flat strip of non-conducting material into the form required for slot insulation and for intermittently feeding the folded strip into a core slot, and mechanism for automatically producing intermittent rotation of the core support relative to the folding and feeding means in order that the core slots will successively receive a folded strip.

3. Armature core insulating apparatus comprising, in combination, means for rotat-

ably supporting a slotted armature core, means for folding a flat strip of non-conducting material into the form required for slot insulation and for feeding a portion of the 5 folded material into a core slot, mechanism for producing intermittent operation of the folding and feeding means, means for automatically severing the portion of the folded material within a core slot from the 10 remainder of the strip, and mechanism for automatically rotating the core relative to the feeding means for the purpose specified.

4. Armature core insulating apparatus comprising, in combination, means for supporting a slotted armature core, means for intermittently feeding a folded strip of insulating material longitudinally with respect to the core into the core slots and mechanism for producing intermittent relative movement 15 between said means in order that the core slots will successively receive said folded strip.

5. Armature core insulating apparatus comprising, in combination, means for supporting a slotted armature core, means for intermittently feeding a strip of insulating material longitudinally with respect to the core into the core slots and mechanism for intermittently rotating the core past the feeding 20 means in order that the core slots will successively receive said strip.

6. Armature core insulating apparatus comprising, in combination, means for supporting a slotted armature core, means for feeding a strip of insulating material longitudinally with respect to the core into the core slots, means for severing the material in the slot from the strip supply, and mechanism for intermittently rotating the core past the feeding 25 means in order that the core slots will successively receive said strip.

7. Armature core insulating apparatus comprising, in combination, means for supporting a slotted armature core, means for feeding a strip of insulating material end- 45 wise into the core slots, co-operating shearing members for severing the material in the slot from the strip supply, means for pushing the severed portion of the material completely into the slot, and mechanism for intermittently 50 rotating the core past the feeding means in order that the core slots will successively receive said strip.

8. Armature core insulating apparatus comprising, in combination, a rotatable collet-chuck for receiving and gripping a shaft upon which an armature core is mounted, a plate rotatable with the chuck and having apertures corresponding to the core slots, means provided by the plate and co-operating 55 with a slot opening of the core to locate the core so that its slots are in alignment with the apertures in the plate, means for feeding insulation pieces through the plate apertures and into the core slots, and means for intermittently 60 rotating the chuck.

9. Armature core insulating apparatus comprising, in combination, a cup shaped member adapted to receive a portion of an armature core and having a locating member 70 adapted to enter a core slot to locate the core definitely relatively to the cup-member, said cup member having in its end wall apertures corresponding to the slots of the core, means for clamping the core to the cup-member, 75 means for feeding insulation pieces through the cup-member and into the core slots, and means for intermittently rotating the cup-member.

In testimony whereof I hereto affix my signature. 80

LORA E. POOLE.
